UNITED STATES PATENT OFFICE.

MICHAEL SWEENEY, OF WHEELING, WEST VIRGINIA, ASSIGNOR TO
SWEENEY, McCLUNEY & CO., OF SAME PLACE.

DESIGN FOR DISHES.

Specification forming part of Design No. 7,364, dated April 7, 1874; application filed February 20, 1874.
[Term of Patent 3½ years.]

To all whom it may concern:

Be it known that I, MICHAEL SWEENEY, of Wheeling, in the county of Ohio and State of West Virginia, have invented a certain Design for Dishes, of which the following is a specification:

The nature of my design is fully represented in the annexed drawings, of which—

Figure 1 is a perspective, and Fig. 2 a section.

My design may be applied to glass dishes of all sizes, and of either an elliptical or a circular form.

The body A of the dish, which is made of glass, terminates on top in a scalloped border, B, resembling a succession of shells, the junction lines of which all converge toward the center of the dish, and are continued on the exterior side in raised ridges to the bottom thereof. These ridges, a, being sharp edges, and so formed that the intervening portions of the body A are concaved, give a pleasing wavy appearance to the interior surface of the

body of the dish, although it is in reality perfectly smooth. At the junction of the body and the border a slight offset, b, is formed upon the interior surface of the dish.

Such dishes, ornamented in the manner described, may be provided with a foot, C, either directly united to the bowl, or connected thereto by means of an intervening stem.

Of course the same design may be used in all kinds of bowled glassware.

What I claim as my invention is—

A design for glass dishes, in which the bowl is ornamented by a scalloped border, B, and exterior sharp-edged ridges a, substantially as shown and described.

In testimony whereof I have signed my name to this specification in the presence of two subscribing witnesses.

M. SWEENEY.
